L. Yale,
Safe Bolt,
No 15,500. Patented Aug. 5, 1856.

2

UNITED STATES PATENT OFFICE.

LINUS YALE, OF NEWPORT, NEW YORK.

BOLT FOR VAULT AND SAFE DOORS.

Specification of Letters Patent No. 15,500, dated August 5, 1856.

To all whom it may concern:

Be it known that I, LINUS YALE, of Newport, in the county of Herkimer and State of New York, have invented a new and Improved Method of Bolting the Doors of Safe-Vaults, &c.; and I do hereby declare the following to be a full and exact description of the same, reference being had to the accompanying drawings.

10 The nature of my invention consists in providing the front edge of the door with a perpendicular bar containing a suitable number—according to the height of the door—of teeth or hooks, standing at an angle of about forty-five degrees, and projecting or pointing toward the rabbet of the jamb, into suitable holes in which, they are forced on closing the door. The points of the said hooks or teeth rest naturally on 15 a level with the holes which they are designed to fill but being formed at an angle of forty-five degrees they, immediately on entering, are crowded upward as well as inward—the bar before mentioned having a 20 sufficient degree of perpendicular movement to accommodate this upward thrust—their extreme movement ending with the complete closing of the door. The lock bolt being now thrown across the perpendicular bar, 25 or into a notch in it provided for that purpose, prevents its moving downward which it must do in order to relieve the teeth from the hole in the jamb, thereby preventing the opening of the door. But by withdraw- 30 ing the lock-bolt a slight draft on the door forces the bar downward as well as outward 35

by means of the slant of the teeth above mentioned thereby relieving their hold upon the jamb and admitting the door to open freely.

40 To enable others skilled in the art to make and use my invention I will describe its construction and operation.

The door A, see drawings and jamb B, are provided with an offset or rabbet a' and b' which match and close flat against each other. Across this shoulder-joint in transverse sec. 1, are short angular hooks c' c' c' attached to and part of bolt-bar C, seen in vertical sec. 2. The bolt d' of the lock D, 45 shoots into a notch of the bolt-bar C, and holds it from a downward or end movement, which is absolutely necessary to allow the door to open, as the before mentioned hooks cannot be drawn straight out of the holes 50 e' e' e' in the jamb B, but must have a double motion viz., downward and outward to be freed from their hold upon the jamb.

55 This motion is given by the motion of the door upon its hinges the closing motion 60 raising the bar and the opening or outward motion depressing the same.

What I claim as my invention and desire to secure by Letters Patent is—

An arrangement of bolts on bars which 65 are self acting in the manner or an equivalent manner to that described and for the purposes set forth.

LINUS YALE.
